UNITED STATES PATENT OFFICE.

ISAAC A. PERRY, OF WILMINGTON, DELAWARE.

RAILWAY-FROG.

SPECIFICATION forming part of Letters Patent No. 313,368, dated March 3, 1885.

Application filed July 7, 1884. (No model.)

To all whom it may concern:

Be it known that I, ISAAC A. PERRY, a citizen of the United States, and residing in Wilmington, Delaware, have invented certain Improvements in Railway-Frogs, of which the following is a specification.

The object of my invention is to so construct a frog for railroads as to dispense with fastening bolts and nuts, and provide for the ready application of the frog to its place or the ready removal of any portion of the frog for renewal or repairs. This object I attain in the manner hereinafter set forth, reference being had to the accompanying drawings, in which—

Figure 1, Sheet 1, is a plan view of a railroad-frog with my improvements; Fig. 2, a longitudinal section on the line 1 2, Fig. 1; Figs. 3, 4, and 5, transverse sections, respectively, on the lines 3 4, 5 6, and 7 8, Fig. 1; Fig. 6, Sheet 2, a perspective view of the parts of the frog detached from each other; and Fig. 7, a view illustrating a modification of part of the invention.

A is the base of the frog, which may be made of cast-iron, malleable iron, wrought-iron, or steel, as desired, and which is spiked or otherwise secured to the cross-ties of the track, and to this base are secured the-point B and wing-rails D D of the frog. The point B comprises two parts—namely, the tongue a and rear block, b, the latter having beveled projections d d', adapted to beveled recesses e e' in the base A, as shown in Fig. 2, so that the block can only be introduced into and removed from its position in the inclined direction shown by the arrow in Fig. 2, all vertical, lateral, or direct longitudinal movement of the block being prevented.

In Fig. 2 the beveled projection d' forms part of a key, f, fitted to an undercut recess in the under side of the block b; but both projections may, if desired, form part of the block, as in Fig. 7. The tongue a of the point of the frog has at the front end a toe, g, which is thrust into an undercut recess, g', in the base A, and is firmly held in position thereby, the rear end of the tongue a abutting against the front end of the block b, and being held in position vertically by a transverse key, h, adapted to key-seats i i in the adjacent ends of these parts, and displacement of

the key is prevented by a projection, k, on the base, and a stop-plate, k', fitted into a recess in the base and retained by a spike, t, or suitable fastening. The wing-rails D are confined by transverse clamp-bars F G and H H', the bars F and G being adapted to recesses p and q in the base A, and the bar F to a recess, w, in the point B. The bar H has on the under side a circular projection, m, adapted to a recess, m', in the base, this projection m being concentric with the confining-bolt n, by which the clamp-plates H H' are secured together and to the base-plate. The projection m serves, 65 with the bolt n, as a bearing on which the wing-rails can swing laterally, as usual, to prevent excessive wear of the point of the frog. The bolt n is prevented from becoming loose by a key, s, driven through an opening 70 in the base and through an opening near the lower end of the bolt, as shown in Fig. 2, and when the point is removed the removal of this key is all that is necessary to release the wing-rails from the base, when the removal of the 75 same or of any of the parts connected therewith becomes necessary. The removal of the spike t is all that is required to release the point of the frog, the parts, however, being so arranged that when in place all parts of said point are 80 firmly and solidly secured to the base. As a consequence of this construction renewal of any of the parts of the frog can be effected in a very short time and with very little labor. When the base of the frog is made of plate 85 iron or steel, the necessary guide-openings and recesses may be formed therein by cutting and bending the plate at the desired points.

I claim as my invention—

1. The combination of the base with the point made of two parts, a and b, having projections adapted to undercut recesses in the base, and with a transverse key, h, adapted to recesses in the two parts of the point, as set forth.

2. The combination of the base, the two parts a and b of the point, the transverse key h, retaining projection k, and detachable plate k', as set forth.

3. The combination of the wing-rails with 100 the transverse clamp-bars F, G, and H, as set forth.

4. The combination of the base having a recess, m', the wing-rails D, and the clamp-

bar H, having a projection, m, adapted to the recess, and a central confining-bolt, n, as set forth.

5. The combination of the point B, having a recess, w, with the wing-rail structure having a bar, F, adapted to said recess, as set forth.

In testimony whereof I have signed my name to this specification in the presence of two subscribing witnesses.

ISAAC A. PERRY.
